UNITED STATES PATENT OFFICE

AURELIO R. TORRES, OF DUARTE, CALIFORNIA, ASSIGNOR OF ONE-THIRD TO ALFRED F. TABERNILLA, OF LOS ANGELES, CALIFORNIA

DISH-WASHING MACHINE

Application filed October 24, 1927. Serial No. 228,342.

My invention relates to dish-washing machines and it has for a purpose the provision of a machine by which dishes of various sizes, as well as table silver, may be washed and rinsed thoroughly, rapidly, and economically, and in a manner to permit the continuous feeding of soiled dishes to the machine with a constant delivery of the washed and rinsed dishes therefrom.

My invention is characterized by employing bodies of washing and rinsing waters instead of water sprays and the attendant waste of water, through which the dishes are continuously and successively moved in such manner that washing and then rinsing of the dishes is effected.

I will describe only one form of dish-washing machine embodying my invention.

In the accompanying drawings:

10 Fig. 1 is a view showing in top plan a dish-washing machine embodying my invention;

Fig. 2 is a vertical sectional view taken on the line 2—2 of Fig. 1;

15 Fig. 3 is a view showing the machine in end elevation;

Fig. 4 is a central vertical longitudinal sectional view of the machine shown in the preceding views;

20 Fig. 5 is an enlarged fragmentary sectional view taken on the line 5—5 of Fig. 4;

Fig. 6 is an enlarged fragmentary sectional view illustrating the manner in which a dish passes beneath one of the confining rollers; 25 and

Fig. 7 is a fragmentary plan view of one of the conveyor belts illustrating the manner in which a dish is washed with the slots of the belt to hold the dish in fixed position 30 thereon.

Referring specifically to the drawings, my invention in its present embodiment comprises a tank including side walls 15, a front end wall 16, a rear end wall 17, and a bottom 18. The tank is divided transversely into compartments 19 and 20 by means of a vertically and centrally positioned partition 21 which, as shown in Fig. 4, terminates short of the top of the tank. An undulated platform 22 is secured within the tank so as

to extend over the upper edge of the partition 21, and this platform is perforated, as indicated at 23, and slotted longitudinally along the inclined portions as indicated at 24. This platform is designed to support the upper stretch 25 of an endless conveyor belt, and to cause such stretch to define a tortuous path corresponding to the contour of the platform. The upper stretch of the conveyor is supported for movement over the platform by means of rollers 26 and 27 arranged at opposite ends of the tank, and an intermediate roller 28 rotatably mounted in a pocket 29 formed in the platform 22 at the upper edge of the partition 21. The roller 26 constitutes a driving roller and on the shaft 30, to which the roller is secured, is a pulley 31 about which is trained an endless belt 32 for operatively connecting the pulley to the shaft of a motor 33. By this connection the motor operates to drive the roller 26 and thereby impart movement to the endless conveyor for moving the upper stretch 25 from right to left as when viewed in Fig. 4. The lower stretch of the conveyor, indicated at 34, is trained beneath rollers and is extended through a slot 36 of the partition 21. These rollers 35 can be made adjustable to tighten the conveyor and thereby insure its proper feeding movement when the roller 26 is rotated.

The endless conveyor is made up of a plurality of separate and independent belts, indicated at B, all of which, however, are trained about the rollers 26, 27, etc., so as to be driven in the same direction by the roller 26. There is one belt for each of a plurality of channels formed by the provision of a plurality of flanges or partitions F secured to and rising from the platform 22 and coextensive in length with the platform. As shown in Fig. 4, the flanges F correspond in contour to that of the platform, while, as shown in Fig. 1, the flanges are spaced apart in such manner that the channels are graduated in width for the purpose of accommodating dishes of different sizes.

Each belt B is constructed of any suitable flexible material and is provided at intervals with transversely extending slots 37 designed

for the purpose of receiving the edges of dishes in a manner to hold the dishes in fixed spaced relation to each other on the belts to prevent piling of one upon another and to thus insure thorough washing of the dishes as they travel through the machine. The manner in which a dish is washed with the belt and slots is clearly illustrated in Figs. 6 and 7.

10 At the delivery end of the machine an inclined and stationary platform 38 is provided for conducting the washed and rinsed dishes downwardly into a receptacle 39. In this receptacle the dishes are deposited and from 15 which they may be removed for wiping. The flanges F may be continued downwardly of the platform 38, and the receptacle 39 divided into compartments corresponding to and registering with the channels formed by the flanges in order that the dishes as collected 20 in the receptacle will remain segregated as to size, thereby facilitating the subsequent storing of the dishes, as will be understood.

In practice, the compartment 19 is filled 25 with soapy water, preferably to the dot and dash line shown in Fig. 4. Water is supplied to the compartment 19 from a faucet 40 arranged thereabove, and with this water soap may be mixed in the required proportions to 30 produce a water which is sufficiently soapy to thoroughly remove grease and other foreign matter adhering to the surface of the dishes. The compartment 20 may be filled with water from a faucet 41. This water is 35 not made soapy as it is designed for rinsing of the dishes previously washed by the water contained in the compartment 19. From time to time it is of course necessary to renew the water in the compartments 19 and 20 and 40 the old water may be discharged therefrom through outlets 42, normally closed by plugs 43, in the form of rods, movable vertically in brackets 44 and provided at their upper ends with handles 45 disposed above the tank 45 and within convenient reach of the operator. It will be understood that by elevating the plugs the outlets could be opened to permit the discharge of water from the tank, the water being delivered to outlet pipes 46.

50 The machine also includes a plurality of rollers 47 as illustrated in Fig. 4. The rollers serve to maintain the belts in contiguous relation to the undulated platform which, as a consequence, causes the dishes to describe 55 the undulated path of movement of the upper stretch of the belts. Transverse rods 48 are extended between and secured to the flanges F at the points shown to reinforce the flanges against spreading. These rods are spaced 60 sufficiently from the belts to permit the dishes to pass therebeneath.

In the operation of the machine, dishes 65 are introduced into the channels defined by the flanges F and from the righthand end of the machine as when viewed in Fig. 4.

The size of the dishes introduced into any particular channel is determined by the width of the channel. I consider this an important feature of my invention as by providing channels of different widths for different-sized dishes, the dishes remain segregated as to size during travel through the machine, thus facilitating the wiping and subsequent storing of the dishes.

The dishes delivered to any particular channel are carried downwardly into the soapy water contained in the compartment 19 by the downward movement of the upper stretch of the respective belt. In passing through the soapy water, the dishes are washed and, under continued movement of the belt, are carried upwardly and free of the soapy water. Under further movement, the dishes are now submerged in the clear water contained in the compartment 20 during 85 which the soapy water is removed from the surface of the dishes so that when they are finally carried upwardly and delivered to the platform 38 they are free of all foreign matter and ready for wiping.

As illustrated in Fig. 2, one of the channels may be greater in depth than the others in order to receive relatively deep dishes such as bowls, the remainder of the channels being constructed to accommodate dishes of conventional sizes, as used in restaurants.

Although I have herein shown and described only one form of dish-washing machine embodying my invention, it is to be understood that various changes and modifications may be made herein without departing from the spirit of the invention and the 100 spirit and scope of the appended claims.

I claim:

1. A dish-washing machine comprising a 105 tank having washing and rinsing compartments therein, a platform undulated to have portions extending into and out of said compartments, flanges rising from the platform for dividing the latter longitudinally into channels, endless belts trained over the platform with one for each of said channels, means for maintaining the belts in contiguous relation to the platform so as to define the same undulations as that of the platform, means by which dishes may be secured to the belts, and means for driving the belts whereby the dishes are successively fed from the washing compartment to the rinsing compartment.

2. A dish-washing machine as embodied in claim 1, wherein the flanges are spaced to form channels of different widths, and the belts are each of a width corresponding to the respective channel.

3. A dish-washing machine comprising a tank having a washing compartment and a rinsing compartment, a perforated platform within the tank undulated to have portions extending into and out of said compartments,

endless perforated belts having portions overlying the platform, means for maintaining the belts in such relation to the platform as to define the same undulations as that of the platform, said belts each having openings therein arranged in groups with the openings of each group so positioned, relatively, as to receive a dish in such manner that the latter is secured to the belt for movement therewith, and means for driving the belts to cause the dishes to be continuously and successively moved through the washing and rinsing compartments.

4. In a dish-washing machine comprising a tank having a partition therein for dividing the tank into washing and rinsing compartments, an undulated platform extending over the partition and having portions extending into said compartments, flanges on the platform for dividing the latter into channels of graduated widths, endless belts having stretches trained over the platform with one for each of the channels, rollers on the flanges above the belts for maintaining the latter contiguous to the platform, means by which dishes may be secured to the belts to travel therewith, and means for driving the belts in the manner and for the purpose described.

AURELIO R. TORRES.
